US0D1019590S

(12) **United States Design Patent** (10) **Patent No.:** **US D1,019,590 S**
(45) **Date of Patent:** **** Mar. 26, 2024**

(54) **IN-VEHICLE ACOUSTIC DEVICE**
(71) Applicant: **ALPS ALPINE CO., LTD.**, Tokyo (JP)
(72) Inventors: **Hideki Endo**, Ota-ku (JP); **Masatada Muramoto**, Ota-ku (JP)
(73) Assignee: **ALPS ALPINE CO., LTD.**, Tokyo (JP)
(**) Term: **15 Years**
(21) Appl. No.: **29/796,654**
(22) Filed: **Jun. 25, 2021**

(30) **Foreign Application Priority Data**

(57) **CLAIM**

The ornamental design for an in-vehicle acoustic device, as shown and described.

DESCRIPTION

FIG. 1 is a perspective view from the front and bottom of an in-vehicle acoustic device showing our new design;

FIG. 2 is a perspective view from the front and top of the in-vehicle acoustic device;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The broken lines depict portions of the in-vehicle acoustic device that form no part of the claimed design.

1 Claim, 8 Drawing Sheets
